UNITED STATES PATENT OFFICE.

WILLARD S. TINKHAM, OF SITUATE, RHODE ISLAND, ADMINISTRATOR OF
WILLARD TINKHAM, DECEASED.

DESIGN FOR A HARNESS-AWL.

SPECIFICATION forming part of Design No. 35,101, dated September 17, 1901.

Application filed May 9, 1901. Serial No. 59,383. Term of patent 7 years.

To all whom it may concern:

Be it known that WILLARD TINKHAM, late a resident of Situate, in the county of Providence and State of Rhode Island, did invent and produce a certain new and useful Design for a Blade for Harness-Awls; and I do hereby declare that the following is a full, clear, and exact description thereof, reference being had to the accompanying drawings, and to the letters of reference marked thereon, which form a part of this specification.

Figure 1 is a side plan view of the design for the blade of a harness-awl. Fig. 2 is a top plan view of the blade. Fig. 3 shows a cross-section of the awl-blade, taken on line 3 3 in Fig. 1.

As shown in the drawings, the leading or material feature of the design consists in the blade being made tapering both in width and depth, as will be observed from Figs. 1 and 2, and semicircular in cross-section for the greater part of its length, and it is also given a longitudinal curve from C to the point D, as set forth in Fig. 1, so that the side that is convex in the cross-section is also convex longitudinally. It will be further observed that

the edges *a a* are convex longitudinally from the tang J to the point D of the blade, and, further, that the middle of the convex portion is given a curve of less radius than the curve of *a a* and which curve is constant until it reaches the extreme end of the blade at D. The edges *a a* meet at the point D and are given a slight curve, as shown in Fig. 2; but the convex part of the blade remains unbroken to extremity of the blade at D. The lower part below where the groove begins is made into a tang J, tapering to a point at its lower end to receive a handle of wood.

Having thus described the invention, what is claimed as new, and desired to be secured by Letters Patent, is—

The design for a blade for a harness-awl herein shown and described.

In witness whereof I have hereunto set my hand this 26th day of April, 1901.

WILLARD S. TINKHAM,
Administrator of the estate of Willard Tinkham, deceased.
